US00D757112S

(12) **United States Design Patent**
Duong

(10) **Patent No.:** **US D757,112 S**
(45) **Date of Patent:** **** May 24, 2016**

(54) **DISPLAY SCREEN WITH GRAPHICAL USER INTERFACE**

(71) Applicant: **Microsoft Corporation**, Redmond, WA (US)

(72) Inventor: **Eric T. Duong**, Seattle, WA (US)

(73) Assignee: **Microsoft Corporation**, Redmond, WA (US)

(**) Term: **14 Years**

(21) Appl. No.: **29/492,470**

(22) Filed: **May 30, 2014**

(51) LOC (10) Cl. **04-14**

(52) U.S. Cl.

USPC **D14/494**

(58) **Field of Classification Search**

USPC D14/489-495; D18/27, 33; D19/6-7;
D20/29-30; 715/700-867, 973-977

CPC G06F 3/04886; G06F 3/04817; G06F 3/0481

(57) **CLAIM**

The ornamental design for a display screen with graphical user interface, as shown and described.

DESCRIPTION

The FIGURE is a front view of a display screen with graphical user interface showing my new design.

The broken line showing of the display screen is included for the purpose of illustrating a portion of the article and forms no part of the claimed design.

1 Claim, 1 Drawing Sheet
